UNITED STATES PATENT OFFICE.

JOHN W. PRIDMORE AND WILLIAM WEBBER, OF CHICAGO, ILLINOIS, AS
SIGNORS TO THE MCCORMICK HARVESTING MACHINE CO., OF CHICAGO,
ILLINOIS, A CORPORATION OF ILLINOIS.

HARVESTER.

SPECIFICATION forming part of Letters Patent No. 712,409, dated October 28, 1902.

Application filed December 28, 1900. Serial No. 41,356. (No model.)

To all whom it may concern.

Be it known that we, JOHN W. PRIDMORE and WILLIAM WEBBER, citizens of the United States, residing at Chicago, in the county of 5 Cook and State of Illinois, have invented certain new and useful Improvements in Harvesters, of which the following is a specification.

Our invention relates to the means for supporting the operative elements of the machine in proper relation to each other and against the various strains to which they are exposed in fieldwork. Its objects are to simplify the construction of the machine, while increasing its stability; to more efficiently secure and sustain its component members in operative relationship and counteract the disturbing forces to which they are subject; to so combine the several mechanisms as to obtain the greatest possible strength with the least weight without obstructing the spaces which for the purposes of the machine should be kept open, and to dispense with parts heretofore employed, while retaining or increasing 25 the advantages which they were intended to contribute.

In the accompanying drawings, Figure 1 is a front elevation of a harvester embodying our invention, omitting certain portions of 30 the machine not material for its illustration. Fig. 2 is a side elevation of the same; Fig. 3, a plan; Fig. 4, a rear elevation; Fig. 5, a detail view from a cross-section on line *x-x*, Fig. 3, looking in the direction indicated by 35 the arrow; and Fig. 6, a detail view of a portion of the support of the binder and parts connected thereto as seen from the opposite side to that shown in Fig. 1.

A represents the main wheel of the harvester; B, the finger-bar; C, the elevator; D, the binder; E, the bundle-carrier. Parts not required for the illustration of this invention are omitted.

1 and 2 are the longitudinal sills on each 40 side of the main wheel.

3 is a bent angle-iron secured at one end to the finger-bar and thence extending across the front ends of the longitudinal sills 1 and 2 and firmly united thereto, thence extending 45 to the front end of the crank-shaft, there

bent to form an elbow, in which is supported the box for the crank-shaft, thence extending upward to form the main support for the grain-binding mechanism. This forms a rigid unitary cross-sill and support, holding and 55 carrying in fixed relation to each other and to the main wheel the cutting mechanism, the driving mechanism, the binding mechanism, the elevator mechanism, and (when desired) the bundle-carrier. On it are mounted 60 the uprights 5 and 6, carrying the front of the elevator. Just above its elbow is secured the bracket 7, in which is pivotally mounted the arm 8 of the bundle-carrier, which is further supported from the upper end of this 65 bent cross-sill by the pivoted rod 9, thus constituting a truss-support for the bundle-carrier. The rod 10, extending from the elevator-frame to the upper front end of the binder-frame, co-operates with this bent cross-sill in 70 firmly supporting the binder in fixed relation to the driving mechanism.

11 is a U-shaped tube extending rearward under the elevator from this bent cross-sill near its junction with the finger-bar, connected to the foot of the elevator-frame both front and rear and to the rear cross-sill 12, behind which it bends upward, then forward, connecting with and supporting the upper elevator-frame at both front and rear and 80 having its front ends united by the upright 13, on which rocks the lever 14, by which the machine is tilted. To the front lower end of this U-shaped tube is pivotally attached a draft rod and brace 15, which connects with 85 the tongue 16, thereby exerting the draft, especially when the machine is turning, directly on that U-shaped element which rigidly supports and ties the machine together both longitudinally and vertically. A clear 90 space for the travel of the grain up the elevator is afforded between the upper and lower arms of the U, and its upper arm supports the seat.

17 is a bracket fitting into the elbow of the 95 bent cross-sill 3, rigidly attached thereto both above and below the bend, having a bearing for the crank-shaft 4 and embracing and rigidly attached to the longitudinal sill 2. It serves at once to reinforce the elbow to firmly 100

secure it to the longitudinal sill and to provide a stable bearing for the crank-shaft in proper relation to both. This crank-shaft has its bearing at the rear end in a bracket 5 18, which fits into the angle of the rear cross-sill and is extended to embrace longitudinal sill 2 and afford a bearing thereon for the driving-shaft 19, being also secured to sill 2 and rear cross-sill 12 at their point of intersection, and to sill 2 in front of shaft 19 it affords, in connection with the front bracket and its supports, a simple but effective means of maintaining the crank-shaft and driving-shaft free from cramping strains and of uniting and bracing the two sills. The lateral or cross sills are formed of angle-iron, with their inner faces fitting over the ends of the hollow longitudinal sills 1 and 2, thus serving to close the ends of these hollow sills while affording a double bearing on them and for the brackets mounted in the angles thereof, making a compact, rigid, and symmetrical construction. Rigidly secured on the rear cross-sill is the bracket 20, which embraces and is firmly attached to the U-shaped member 11, fits against and is rigidly attached to the foot of the elevator-frame and the grain-platform, respectively, and contains a bearing for the driving-shaft 23 of the platform-apron. This affords an efficient locking together of the U-shaped member, the elevator-frame, the sill, and the platform, and braces these parts upon each other.

21 is a rod extending from the top of the elevator-frame to the binder-supporting post 22.

25 is the sliding tube of the binder, which is supported in a bracket on the upper end of sill 3 and slides on the antifriction-wheel 24, mounted in said bracket, as shown in Fig. 40 6. By this construction, of which the U-

shaped element uniting and supporting the mechanisms longitudinally and vertically and the front bent cross-sill uniting and supporting them laterally and vertically are the dominating features, we secure great strength 45 and rigidity in the composite machine and dispense with many parts before required, while securing better results.

We claim—

1. In combination with the U-shaped longitudinal and vertical support, the draft and brace rod attached to the front of the lower arm and extending thence to the pole, for the purpose described.
2. In combination with the U-shaped longitudinal and vertical support, the upright uniting its front ends, and the tilting lever mounted thereon, substantially as described.
3. The combination of the front cross-sill bent upward and forming a support for the binding mechanism, the bracket mounted on the upward bend thereof adapted to pivotally support a bundle-carrier, a bundle-carrier, and a rod pivotally connected to said upward bend above said bracket and to the bundle-carrier, substantially as described.
4. In combination with the cutting, binding and bundle-carrying mechanism of a harvester, the front cross-sill connecting the same, and a bracket mounted on an upward extension of said sill having a sliding bearing for the binder and a pivoted connection for a rod extending therefrom to and supporting the bundle-carrier, substantially as described.

JOHN W. PRIDMORE.
WILLIAM WEBBER.
